United States Patent

Des. 240,316
Patented June 22, 1976

240,316

RELIGIOUS SYMBOL OR THE LIKE

William R. Elliott, 7216 Ainsley St.,
Fayetteville, N.C. 28304

Filed Aug. 19, 1974, Ser. No. 498,438

Term of patent 14 years

Int. Cl. D11—02

U.S. Cl. D29—11 C

FIG. 1

FIG. 2

FIG. 3

FIG. 4

FIG. 5

FIG. 1 is a front elevational view of the religious symbol or the like showing my new design;

FIG. 2 is a rear elevational view of such design;

FIG. 3 is a top plan view of the same;

FIG. 4 is a bottom plan view of such design; and

FIG. 5 is a side elevational view of the same, the opposite side being substantially a mirror image of that shown.

I claim:

The ornamental design for a religious symbol or the like, as shown.
